UNITED STATES PATENT OFFICE

SVERRE RASMUSSEN, OF NEW YORK, N. Y.

AEROPLANE

Application filed December 28, 1928. Serial No. 328,820.

This invention relates to aeronautics and more particularly to a machine of the heavier than air type sustained in flight by the speed at which it moves.

An object of the invention is to provide an aeroplane with an improved type of wings which are rotatably mounted and are not only very effective in supporting the machine in flight but also cause the machine to travel at a higher rate of speed when in flight by reducing friction and allow it to land safely while traveling at a very low speed.

Another object of the invention is to further reduce the area of reduced pressure. This is accomplished by the whirling motion of the air produced above the wings by the rotary motion of the circular wings.

Another object of the invention is to prevent danger of a side slip when making a turn or accidentally getting into a side slip when flying straight ahead.

Another object of the invention is to provide the rotary wings with auxiliary blades ordinarily retracted therein but allowed to be released by the aviator and moved outwardly from the peripheries of the wings and rotate the same when acted upon by air currents if the engine fails and a forced landing is necessary.

Another object of the invention is to provide an improved arrangement of ailerons.

Other objects and advantages of the invention will hereinafter appear and the novel features thereof will be specifically defined by the appended claims.

The invention is illustrated in the accompanying drawings, wherein,

Figure 1 is a top plan view of the improved aeroplane,

Figure 2 is a front elevation thereof,

Figure 3 is a view showing the same in side elevation.

Figure 4 is a top plan view of one of the planes with a portion of the fabric removed.

Figure 5 is a fragmentary view of a wing with an auxiliary blade extended,

Figure 6 is an edge view of a fragment of a wing.

Figure 7 is a fragmentary sectional view of

the central portion of a wing and operating means associated therewith.

The aeroplane illustrated in the accompanying drawings is in some respects of a conventional construction and includes a fuselage 1 having a motor and propeller at its front as shown at 2 and 3, and at its rear provided with the usual rudder 4 and stabilizers 5.

Tubular casings 6 project from opposite sides of the fuselage 1 which are braced by rods leading from housings 7 at the outer ends of the casings and are secured to the fuselage. Drive shafts 8 extend through the casings 6 with their inner end portions extending into the fuselage and carrying bevelled gears 9 which mesh with a gear 10 upon the shaft of an engine 11 mounted in the fuselage rearwardly of the main engine 2. At their outer ends the shafts 8 carry bevelled gears 12 meshing with gears 13 of posts 14 journaled vertically in the housings 7 and projecting upwardly therefrom. These posts carry wings 15 and at their upper ends are provided with hollow heads 16 constituting hubs for the frames of the wings.

The wings are disposed at opposite sides of the fuselage and each is in the form of a circular disk as shown in Fig. 1. From the hub 16 of each wing radiate ribs 17 joined by hoops 18 intermediate their end and at their outer ends by a bordering hoop or band 19 which defines the entering edge of the wing when the fabric 20 is applied to the frame, as shown in Figures 2 and 3. Cross strips 21 extend between the ribs 17 and these strips carry guides serving to retain springs 23 in their proper positions about stems 24 which project from the inner ends of auxiliary blades 25 which are slidably received in the wings and disposed in angular relation to the entering edges thereof as shown in Figures 2, 3 and 6. Since the springs bear against the inner strips 21 and abutments 26 carried by the stems 24 they serve to urge the blades 25 towards the extended position shown in Figure 5, but under normal conditions these blades are to be retracted. In order to releasably secure the blades retracted the inner ends of the stems are formed with hooks 27 for engagement by latches 28 pivoted in

openings in the hub 16 and these latches are yieldably retained in engagement with the hooks 27 by springs 29.

In order to release the latches I provide each post with an axially extending bore in which is received a shaft 30 and this shaft has a head 31 at its upper end and a base or foot 32 at its lower end. The head engages beneath the inner ends of the latches and the foot rests upon a cam 33 carried by a rocker 34 so that when the rocker is rotated through the medium of a pull cord 35 the shaft will be elevated and through the medium of its head move the latches to release the stems 24. The pull cords extend through tubes 36 into the fuselage where they may be reached by the pilot when necessary.

When the aeroplane is in use it is propelled forwardly by its engine 2 and propeller 3 in the usual manner. The motor 11 imparts rotary motion to the drive shafts 8 from which rotary motion is imparted to the posts 14 and wings 15. It will thus be seen that the wings will rotate in a horizontal plane instead of being rigid with the fuselage. Since the wings rotate, friction will be reduced and the speed of the machine increased. This will cause it to take off after a very short run and in addition increase its speed when in flight. The rotation of the wings also creates a force similar to a gyroscope which causes the machine to be very steady in flight and eliminates danger of its tilting and getting into a side slip. It should also be noted that since the rotating wings steady the machine when in flight it can land when traveling at a low rate of speed without danger of being damaged.

If for any reason the motor 11 should fail to operate properly and cease to impart rotation to the wings, the pilot draws upon the pull cord 35 thereby causing the shafts 30 to be elevated and move the latches to release the stems so that the springs 23 may force the blades 25 outwardly to the extended position shown in Figure 5. When so extended the air currents created by the moving machine will act against the extended blades and cause the wings to continue their rotary motion. Even if both motors should fail the wings may be caused to rotate in this manner and a forced landing safely made.

When making a turn or executing a roll or the like while flying it is necessary to tilt the machine transversely in order to bank it at a turn or cause it to turn about its longitudinal axis and this is usually carried out through the means of ailerons consisting of small planes pivotally mounted with respect to the main wings. Ailerons of the usual type cannot be used with rotating wings and I have therefore provided ailerons in the form of small planes or wings 37, loosely mounted upon the casings 6 and adapted to be tilted about the same. Any means desired may be

employed whereby the aviator may tilt the ailerons or wings 37 simultaneously but in opposite directions.

What I claim is:

1. An aeroplane comprising a fuselage, 70 disk-like wings at opposite sides of said fuselage each mounted to rotate in a horizontal plane, main driving means for imparting rotary motion to said wings, and normally inactive radially disposed means carried by said 75 wings adapted to be acted upon by air currents and rotate the wings when the main driving means is inoperative.

2. An aeroplane comprising a fuselage, 80 disk-like wings at opposite sides of said fuselage each mounted to rotate in a horizontal plane, main driving means for imparting rotary motion to said wings, means for imparting rotation to said wings including a source of power and transmitting means leading to 85 the wings, and auxiliary means for rotating said wings carried thereby and movable into and out of an operative position.

3. An aeroplane comprising a fuselage, 90 disk-like wings at opposite sides of said fuselage each mounted to rotate in a horizontal plane, main driving means for imparting rotary motion to said wings, means for imparting rotation to said wings including a source of power and transmitting means leading to 95 the wings, and auxiliary means for rotating said wings carried thereby and slidable from a retracted position within the wings to an extended position for use.

4. An aeroplane comprising a fuselage, 100 disk-like wings at opposite sides of said fuselage each mounted to rotate in a horizontal plane, main driving means for imparting rotary motion to said wings, means for imparting rotation to said wings including a source 10 of power and transmitting means leading to the wings, and auxiliary means for rotating said wings, including blades slidable radially from a retracted position to an extended position for use, stems extending from the inner ends of said blades, means to urge said blades outwardly, and means to engage said stems and releasably hold the blades retracted.

5. An aeroplane comprising a fuselage, 110 supports extending from opposite sides of said fuselage, circular planes at opposite sides of said fuselage, posts at the centers of said planes journaled in said supports to rotatably mount the planes, a motor in said fuselage, and shafts rotated from said motor and extending from opposite sides of the fuselage and connected with said posts to impart rotation to the posts and planes and radially-movable auxiliary driving means, normally 120 inactive.

6. An aeroplane comprising a fuselage, 120 supports extending from opposite sides of said fuselage, circular planes at opposite sides of said fuselage, posts at the centers of 130

5 said planes journaled in said supports to rotatably mount the planes, a motor in said fuselage, means for transmitting motion from the motor to said posts to rotate the posts and planes, normally inactive but radially movable when desired, and means carried by said planes whereby air currents may effect rotation of the planes when the motor is out of operation.

10 7. An aeroplane comprising a fuselage, supports extending from opposite sides of said fuselage, circular planes at opposite sides of said fuselage, posts at the centers of said planes journaled in said supports to rotatably mount the planes, a motor in said fuselage, means for transmitting motion from the motor to said posts to rotate the posts and planes, blades slidably mounted in said planes, stems extending from the inner ends of said blades, springs acting upon said stems to urge the blades outwardly, latches for engaging said stems and releasably holding the blades retracted, and means for moving said latches out of engagement with the stems whereby the blades may move outwardly and project radially from the peripheries of the planes.

15 8. An aeroplane comprising a fuselage, supports extending from opposite sides of said fuselage, housings at the outer ends of said supports, circular planes over said supports at opposite sides of said fuselage, posts depending from the centers of said planes and journaled in said housings, means for imparting rotary motion to said posts to rotate the planes, hollow heads at the upper ends of said posts within the planes, blades slideable radially in the planes, stems extending from the inner ends of said blades and having hooks at their ends, springs urging said blades outwardly, latches for engaging the hooked ends of said stems to hold the blades retracted pivoted to said heads and projecting into the same rotary rods extruding through said posts and having heads at their upper ends to engage the inner ends of said latches and their lower end projecting from the posts, and means to move the rods upwardly and release said latches including cams turnably mounted below the rods and contacting therewith and actuating lines extending through said support into the fuselage.

20 9. An aeroplane comprising a fuselage and disk-like wings, mounted at opposite sides of the fuselage, means to rotate said wings in a horizontal plane, and auxiliary means radially-movable for rotating said wings when the driving means becomes inoperative.

25 60 In testimony whereof I affix my signature.
SVERRE RASMUSSEN.
